UNITED STATES PATENT OFFICE

2,632,422

COATING APPARATUS

Frank S. Elkins, Passaic, N. J., assignor to United States Rubber Company, New York, N. Y., a corporation of New Jersey

Application November 30, 1950, Serial No. 198,310

1 Claim. (Cl. 118—415)

1

This invention relates to apparatus for applying a coating composition to continuous lengths of sheet materials, and more particularly it relates to a new and improved coating blade structure.

One object of the invention is to provide a coating blade for coating paper, cloth, and the like, that can be cleaned conveniently without dismantling the coating apparatus.

Another object is the provision of a coating applicator assembly that can be adapted readily to use with coating compositions of various characteristics or to application of coatings of various thicknesses.

Still another object is the provision of a coating apparatus that requires relatively little labor or lost time for periodic servicing in the course of operation of the apparatus.

The foregoing and other objects and advantages of the invention will be made evident in the following detailed description, which is intended to be read with reference to the accompanying drawings, wherein

Fig. 1 is an elevational view, partly in section, of an apparatus for coating continuous lengths of cloth and the like, showing the improved coating applicator of the present invention in operative position;

Fig. 2 is a fragmentary perspective view of portions of the apparatus of Fig. 1; and

Fig. 3 is a fragmentary cross-sectional view of a modification of the improved applicator.

The invention provides an improved coating blade which takes the form of a slotted tube that is slidably mounted on a mounting plate which passes through the slot in the tube, in frictional engagement with the edges of the slot, into the interior of the tube. The exterior surface of the slotted tube serves as the bearing or coating surface during the coating operation.

Referring to Fig. 1, the coating apparatus shown therein is represented as applying to a continuous length 10 of sheet material, such as cloth or the like, a coating 11. The cloth 10 is fed continuously upwardly from a supply roll 12 and passes generally horizontally over the upper surfaces of two spaced transverse idler rollers 13, 14 supported at their ends in suitable bearings 15, 16 attached to vertical legs 17 and 18 of a side frame member 19, one of such frame members 19 being disposed at each side of the machine.

An applicator assembly 20 is arranged to bear against the upper surface of the cloth 10 or like material between the two idler rollers 13, 14. 55

2

The applicator assembly includes a body plate 21 that runs transversely of the coating applicator. The body plate has fixed on one of its faces a shaft 22 which projects outwardly from each end of the body plate and extends rotatably at each of its ends, into a bearing block 23 mounted slidably for vertical movement between the legs 17 and 18 of the side frame 19.

The bearing block may be adjusted vertically 10 to position the applicator assembly at the desired horizontal level by turning a hand wheel 24 on a horizontal shaft 25 that is rotatably supported at each side of the apparatus in a bearing member 26 extending upwardly from an upper transverse section 27 of the end frame 19. A bevel gear 28 fixed to the horizontal adjusting shaft engages a bevel gear 30 on the upper end of a vertical adjusting shaft 31 that extends downwardly through the transverse frame section 27, in rotatable engagement therewith, into the sliding bearing block 23. The lower section of the vertical adjusting shaft passes screw-threadedly through a vertical hole provided in the block 23 in such manner that rotation of the shaft causes the block to be raised or lowered. A collar 32 fixed to the vertical shaft at the underside of the transverse frame section 27 maintains the shaft in place. It will be understood that the adjusting means described is duplicated at each side of the machine, each of the adjusting assemblies being operated as a unit through the medium of the horizontal adjusting shaft 25.

The opposite face of the body plate 21 of the applicator assembly has a relatively thin flat mounting plate member 33 securely attached thereto by means of spaced screws 34 which pass through the mounting plate into the body plate. The lower edge of the mounting plate 33 carries a coating tube 35 which has a longitudinal slot 36 through its upper surface of such width that the mounting plate 33 passes slidably therethrough into the interior of the tube. There is sufficient frictional resistance between the edges of the slot and the faces of the mounting plate to maintain the tube in position on the plate. When the tube 35 is in operative position the lower edge 37 of the plate 33 engages the lower inner surface 38 of the tube.

At either end of the tube 35 there is provided a vertical barrier plate 39 which extends outwardly from the front surface of the applicator assembly and which is secured to a bracket 40 slidably adjustable along the length of the applicator assembly by means of a nut and bolt

41 passing through the bracket and through an elongated slot 42 extending lengthwise across the body plate 21. The barrier plate is vertically adjustable by means of a nut and bolt 43 passing through the barrier plate and through a slot 44 in the bracket 40. By this means the barrier plates may be adjustably positioned as desired along the length of the applicator assembly and may be raised or lowered to position the lower edge of the plates at the marginal surfaces of the cloth 10, thereby serving to maintain a body 45 of coating liquid, supplied from a suitable source (not shown) in place on the cloth 10 in engagement with the coating tube.

As indicated in Fig. 1, when the applicator assembly is in operative position, the assembly is usually inclined with respect to the cloth 10. The angle of the applicator assembly may be adjusted about the shaft 22 as a pivot point to vary the thickness of the coating by means of a horizontal adjusting screw 46 which is threaded through a bracket 47 on the leg 18 of the side frame. The end of the adjusting screw 46 engages the rear face of the body plate 21, and by threading the screw 46 inwardly or outwardly the angle of the assembly may be varied.

After passing from the applicator assembly, the cloth 10 containing the coating 11 may pass into an oven 48 in which the coating is dried, or otherwise heat-treated, depending on the nature of the coating, after which the coated cloth may pass to a suitable wind-up (not shown).

The operation of the foregoing apparatus is efficient and convenient. The apparatus is easily set up and adjusted by a single operator, who can handle the relatively light slotted coating tube 35 without difficulty even though the tube may in practice be relatively long, say 7 feet. To set up the apparatus for a coating operation, the operator simply slips a slotted tube of suitable diameter over the edge of the mounting plate, and adjusts the barrier plates 39 to the proper width. The applicator assembly is adjusted at a suitable vertical position by turning the horizontal adjusting wheel 24, while the angle of the assembly may be fixed by adjusting the screw 46. The cloth 10 or other material to be coated is passed through the apparatus, and a supply of the coating composition is introduced to the surface of the cloth before the applicator assembly to form a body 45 of the coating composition. As the cloth passes underneath the coating tube in engagement with the outer surface of the tube and in pressurized contact therewith, a thin continuous coating 11 is applied evenly over the surface of the cloth.

Various sizes of slotted coating tubes, disposed at various angles, may be employed to give coatings of the desired characteristics. In the modification shown in Fig. 3, a somewhat larger tube 50 is employed than that shown in Figs. 1 and 2, and the tube is shown operating with the mounting plate 51 in a vertical position. The angle of the applicator to the advancing cloth affects the characteristics of the coating. For example, as the angle of the applicator approaches 90° as shown in Fig. 3, the pressure on, and the tension of the cloth, or other material being coated, increases, and the thickness of the applied coating diminishes. When the applicator is at an acute angle to the advancing cloth the coating will generally be thicker than when the applicator is at an obtuse angle, as indicated in Fig. 1.

The external diameter of the slotted tube also affects the characteristics of the coating. In

general, tubes of large diameter give a thicker coating than tubes of small diameter.

The coating tube may be made of various materials. Stainless steel, copper and brass are especially suitable.

It will be noted that the sheet material 10 being coated contacts the slotted tube at a point 52 on its outer surface which is not diametrically opposed to the slot, but is located to one side of the surface 53 diametrically opposed to the slot, in the direction of approach of the material. This is because the forward movement of the sheet material tends to displace the tube slightly in the direction of travel of the material so that the edge 54 of the tube slot engaging the rear face of the mounting plate is raised slightly higher than the edge 55 engaging the front face of the mounting plate. Therefore, if the tube is mounted in a reversed position, a different portion thereof becomes the principal wearing surface. This is advantageous since the wear on the tube surface may be distributed over a greater area than would be possible if the sheet material contacted the tube at a point diametrically opposed to the slot, which point would be the principal wearing surface regardless of which way the tube was mounted on the mounting plate. The foregoing advantage is realized both when the applicator assembly is operated in a vertical position as in Fig. 3, or at an angle to the vertical, as in Fig. 1.

In the course of the coating operation it is occasionally necessary to clean the coating surface, which tends to become fouled with excess coating material producing an uneven or striated coating. With the present apparatus cleaning is easily accomplished by a single operator by turning the applicator assembly upwardly out of operative position, whereupon the operator can easily slip the slotted tube constituting the applicator surface off the mounting plate by hand, clean it, and replace it again by hand, all without dismantling parts of the apparatus. This convenience is largely a consequence of the fact that the slotted tube requires no bolts or other mechanical connection to the remainder of the applicator assembly, but may be maintained in place by simply frictional engagement with the mounting plate, as described.

The slotted coating tube is readily adaptable to use with conventional coating apparatus, since the tube may be easily inserted over a regular knife coating blade.

Since the slotted tubes are light in weight and inexpensive to fabricate, a variety of such tubes of different diameters and lengths may be provided to render a given coating apparatus capable of performing a variety of coating operations on paper or other material of various widths. A changeover from one diameter to another may be accomplished without dismantling the apparatus.

The coating applicator including the slotted coating tube described results in even coatings of good quality.

Having thus described my invention what I claim and desire to protect by Letters Patent is:

A coating apparatus comprising a pair of spaced vertical supports, means for advancing a material to be coated between said supports in a generally horizontal direction, a mounting plate supported between said vertical supports above the advancing material and transversely to the path of the advancing material, a coating blade that is a hollow tube having a longitudinal slot in its upper 75 wall, said blade being detachably mounted at the

lower edge of said mounting plate, said mounting plate extending downwardly through the longitudinal slot so that the lower edge of the plate is in proximity to the lower, interior surface of said tube, said tube being held to said mounting plate by friction between the two faces of the longitudinal slot and the exterior side faces of the mounting plate, said slotted tube and said mounting plate being so positioned in the coating apparatus that the lower exterior surface of the tube bears on the material passing through the coating

apparatus so as to thereby permit continuous application of a surface coating to the material.
